Primary Examiner — Garth Rademaker*Assistant Examiner* — Kristy N. Nilsson(74) *Attorney, Agent, or Firm* — Bonini IP Law, LLC; Frank J. Bonini, Jr.(57) **CLAIM**

The ornamental design for a rail car side screen protector as shown and described.

DESCRIPTION

FIG. 1 is a top perspective view of a rail car side screen protector showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines in the figures illustrate the portions of the article that form no part of the claimed design.

1 Claim, 4 Drawing Sheets(56)
